UNITED STATES PATENT OFFICE.

JAN BIRGEL, OF DAWSON, NORTH DAKOTA.

DESIGN FOR A HALTER-RING.

SPECIFICATION forming part of Design No. 34,113, dated February 19, 1901.

Application filed January 25, 1901. Serial No. 44,766. Term of patent 14 years.

To all whom it may concern:

Be it known that I, JAN BIRGEL, a citizen of the United States, and a resident of Dawson, in the county of Kidder and State of North Dakota, have invented and produced a new and original Design for a Halter-Ring, of which the following is a full, clear, and exact description.

Reference is to be had to the accompanying drawing, forming a part of this specification, in which the figure shows a halter-ring embodying my design.

The leading feature of my design for a halter-ring consists of a straight member at one side, opposite which are converging straight members, and arranged between these members are opposite inwardly-curved members.

Referring particularly to the drawing, 1

designates the straight member of the halter-ring, 2 and 3 the straight converging members opposite the member 1, and 4 and 5 the opposite inwardly-curved members, the curved member 4 being shorter than the curved member 5.

Having thus described my invention, I claim as new and desire to secure by Letters Patent—

The design for a halter-ring as herein shown and described.

In testimony whereof I have signed my name to this specification in the presence of two subscribing witnesses.

JAN BIRGEL.
